RESISTOR SPOOL

Richard W. Hull, Pasadena, Calif., assignor to
 Consolidated Engineering Corporation, Pasadena, Calif., a corporation of California

Application September 28, 1946, Serial No. 699,982

1 Claim. (Cl. 242—118)

1

This invention relates to electrical coil devices of the type wound-on spools such as inductances and resistances.

The principal object is to provide a spool construction for such wire-wound structures as will minimize the likelihood of damage to the wire coil and its insulation.

It is a common practice to wind coils of insulated wire on a spool to provide inductance or resistance elements. In the case of resistance elements, it is often desired to make them of the non-inductive type, and this requires reversal of the direction of winding at relatively short intervals, according to a well-known practice. The reversals of direction are frequently performed by the provision of a spool having a number of winding spaces or sections arranged around the longitudinal axis of the spool; and slots are cut in the partitions between the sections to enable the wire to be carried through from one section to the next. It ordinarily happens that when the wire is carried through a slot from one spool section to the next, it will be carried down around the inside circumference of the spool, so that subsequent layers of the wire will be wound around and rub along the strand which has first been carried down. This will frequently wear off the insulation from the strand and sometimes produces short circuits.

In accordance with my invention, I provide a spool construction which minimizes the undesired scraping and wearing off of the wire insulation. I carry out my invention by the provision of a spool having through its end member and/or partitions a slot which is off center, that is, extends along a segment of the spool section rather than through its center.

A feature of my invention is the provision of a pair of slots at the partition, and preferably the slots are tangential to the core of the spool. According to one embodiment, for example, the slots are parallel to each other and on either side of the center line. According to another embodiment, the slots are non-parallel and converge toward each other.

When the wire is carried through such slots, the wire comes down approximately tangential to the core of the spool so that subsequent turns of the wire do not rub against the original strand which has been carried through, and this minimizes the tendency toward damage to the insulation.

The foregoing and other features of my invention will be better understood from the following detailed description and the accompanying drawings of which:

2

Fig. 1 is a side view of a spool in accordance with my invention;

Fig. 2 is an end view of the spool;

Fig. 3 is an enlarged view showing part of the spool with windings represented on it;

Fig. 4 is a cross-section view taken at line 4—4 of Fig. 3;

Fig. 5 is another enlarged view of part of the spool showing a different arrangement of windings on it;

Fig. 6 is a cross-section view taken at line 6—6 of Fig. 5;

Fig. 7 is a side view of a modification according to my invention; and

Fig. 8 is a cross-section view taken at line 8—8 of Fig. 7.

Referring to Fig. 1, the spool 1 comprises a pair of circular end members 2 and 3 between which are located a number of partitions 4 at spaced intervals apart, dividing the spool into a number of winding sections 5. The spool may be of any suitable material, for example, bakelite or a rubber composition which will serve to hold the insulated wire winding. Each of the spool partitions 4 is in the form of a member having conical sides tapering to a narrower thickness at the outside, as shown in Fig. 1, so that each spool is provided with a central core 6 and outwardly tapering sides, this configuration being well adapted to receive a wire winding.

It is desired that a single continuous winding be carried from one spool section to another, and for this purpose each partition is provided with a pair of slots 7 and 8, the slots being parallel to each other and extending from the circumference of the partition to the core 6 of the spool. The slots are not arranged along a diameter of the partition, but instead, are arranged along a line forming a segment of the partition, and are spaced so that the direction of the slot is substantially tangential to the circular core 6 where the slots meet the core. This arrangement is illustrated in Fig. 2.

To form a coil for a resistor winding, an insulated wire will be wound in the sections 5 of the spool. Fig. 3 shows such a winding, which is wound as a non-inductive resistance. The winding is formed by an insulated wire 9 which may be a well known type of covered wire such as an enamel-coated wire. The winding is started by inserting the wire into the slot 7 of the end piece 2, where it will be suitably fastened or attached to a terminal member. This attachment is made in the embodiment illustrated by the provision of a terminal wire 10 which is inserted in a peripheral groove 11 around termi-

nal piece 2, the wire 10 being suitably twisted at 12 to hold a loop of the terminal wire tightly in the groove while allowing a convenient length of the terminal portion to protrude from the spool. The insulation will be scraped from wire 9 where it meets terminal wire 10 at groove 11 of the end piece, and it may be looped over the wire 10 and fastened by solder 13.

The wire 9 from the slot 1 is carried down into the winding section and wound on the spool in a counterclockwise direction (as viewed from the left end of the spool in Fig. 3), until a sufficient amount of the winding has been put into the section. Then the outermost strand of the winding is carried through the slot 8 of the first partition member nearest the end member 2, and the wire is brought down to the cylindrical base of the spool in the second section, and the winding is formed in the second section in the clockwise direction, that is, opposite to the direction of winding in the first section.

In passing through the next partition, the wire will be brought through the slot 8 on the other side of the axis of the spool, and the winding in the following section will be reversed, that is, wound counterclockwise like in the first section. In this way, the wire is brought through successive partitions through the alternate slots 7 and 8, and the windings in the successive sections are alternately clockwise and counterclockwise. It will be recognized that this change of direction of the winding will create a substantially non-inductive type of resistance. At the end member 3, the end of the winding may be connected to a terminal wire such as the wire 15 which may be attached similarly to the attachment of terminal wire 10.

It may, under some circumstances, be desired to wind all of the sections of the spool in the same direction. This can be done just as well as winding them in opposite directions as in Fig. 3. Fig. 5 shows an arrangement in which the sections are wound in the same direction. In Fig. 5, the winding is carried down from the terminal wire 10 and wound in a clockwise direction in the first section of the spool, in a manner similar to the winding in the first section of Fig. 3. Then when the first section has received its full winding, the wire instead of being brought down through the opposite slot 7 is carried through slot 8 of the first partition; and in starting the winding in the second section, its direction is continued in the clockwise direction. The wire is carried through all subsequent partitions through the slot 8 on the same side of the axis of the spool, and the windings are all in the same direction.

The tapered shape of the spool partitions 4 is especially advantageous when shrinkable material for the spool is used. Bakelite and some other spool materials, for example, shrink with age so that the length of the spool tends to decrease somewhat. This has the effect of tending to compress and squeeze the windings in the sections. By reason of the tapered sides to the partitions, however, the winding is enabled to be squeezed outwardly somewhat if and when such shrinkage occurs, without the attendant danger of damage to the winding and its insulation if no room for squeezing out were permitted.

Another modification of a spool made according to my invention is illustrated in Figs. 7 and 8. In this embodiment there is provided the central cylindrical core 16 with its two end members 17 and 18 and partitions 19 separating the spool into sections. The end members and the partitions differ

somewhat from those in Figs. 1 to 6, in that they do not taper toward the core of the spool, but instead, are in planes perpendicular to the longitudinal axis of the core. The slots 20 and 21 through the end sections and partitions, instead of being parallel to each other as in the preceding embodiments, are at an angle to each other as shown in Fig. 8. In Fig. 8, the angle between slots 20 and 21 is shown as being substantially 90°, although it will be understood that some other angle might be used instead if desired. The slots, although at an angle to each other are arranged to be substantially tangential to the core where they meet the core.

Except for the difference in angularity of the slots, and other details such as the taper of the partitions, the windings in the spool may be made the same as the embodiments in Figs. 1 to 6, and the windings may be made the same way. The construction of Figs. 7 and 8 may have advantages over that of Figs. 1 to 6 in specific instances, for example, where the spool material is more brittle than is being used in the embodiments of Figs. 1 to 6. Where a brittle material is being used, for example a ceramic or the like, it may be undesirable to space the slots close together and parallel to each other as in Figs. 1 to 6, and instead to space them somewhat further apart as shown in Figs. 7 and 8, to provide additional strength. Moreover, it may in some instances be undesirable to use tapered partition sections as shown in Figs. 1 to 6, and instead to use the straight-sided sections as shown in Figs. 7 and 8.

When straight-sided partitions are used such as is shown in Fig. 7, a spool material will usually be selected which does not shrink appreciably with age. A ceramic or porcelain material, for example, does not shrink much, and the coefficient of expansion of a ceramic is usually even less than that of the wire.

By my novel forms of spool provided with slots arranged according to my invention, it will be recognized that I have provided means whereby the windings in a spool may be made without such serious risk of injury to the insulation on the wire as if only a single centrally located slot were used, as has heretofore been the practice. By carrying the initial lead of a spool section down through the slot which is substantially tangential to the inner cylindrical core of the spool on which the winding is to be carried, there is very little scraping of subsequent lays of the winding over the initial wire which is carried through.

It will be recognized that if a single slot were used and the wire carried down through the single slot, it would be bent in direction at the position where the slot meets the spool; that is, it will turn at almost a right angle in the direction of the tangent to the spool cylinder at the base of the slot. This will result in the subsequent turns of the wire striking the right angle bend and scraping the insulation off. If it should happen that the insulation should similarly be scraped off one of the subsequent turns, there would be a resulting short circuit of the turns.

By using the slot which is substantially tangential to the spool, in accordance with my invention, there will be no bend of the wire at the point where the slot lets the entrance wire into the base of the spool, and accordingly less likelihood of damage to the insulation.

It will be recognized that my invention is not limited to the particular embodiments shown in the drawing, which are given for illustration pur-

poses rather than for purposes of limitation. Other modifications within the scope of my invention will suggest themselves to those skilled in the art. For example, the advantage of my invention will be obtained even though the spool has only a single section for winding. In such a case, the advantage will be had on the carrying down of the initial length or strand of wire from the terminal position to the base of the spool.

I claim:

A spool having a core for holding an electrical winding comprising a section in which the winding is placed and a boundary wall at each end of the section, at least one of the boundary walls having a pair of slots off center with reference to the plane which passes through the longitudinal axis of the spool and extending from the periphery of the partition to the core of the spool for passage of the lead in wire to the section, said slots being at substantially a ninety degree angle with respect to each other and lying in planes which

are substantially tangential to the core of the spool where the slot meets the core.
